ALL PURPOSE CAGE TRUCK

Glenn E. Mueller, Richmond Heights, Mo., assignor to Oberon Steel Products Company, Clayton, Mo., a corporation of Missouri

Filed May 29, 1963, Ser. No. 75,112

Term of patent 14 years

(Cl. D14—3)

FIG. 1.

FIG. 3.

FIG. 2.

FIG. 4.

FIG. 6.

FIG. 5.

FIG. 7.

FIG. 8

FIG. 1 is a top plan view of an all purpose cage truck showing my new design;

FIG. 2 is a front elevation of FIG. 1;

FIG. 3 is a rear elevation of FIG. 1;

FIG. 4 is a right side elevation of FIG. 1;

FIG. 5 is a left side elevation of FIG. 1;

FIG. 6 is a bottom plan view of the truck;

FIG. 7 is a perspective view of the truck showing it in an opened condition; and

FIG. 8 is an enlarged fragmentary sectional view thereof taken on lines 8-8 of FIG. 4.

I claim:

The ornamental design for an all purpose cage truck, substantially as shown.
